F/G. 1

F/G. 2

FIG. 3

FIG. 4

FIG. 1 is a front perspective view of a combined telephone handset and desk stand showing my new design;

FIG. 2 is the same view as shown in FIG. 1 with the handset elevated;

FIG. 3 is a top plan view of the desk stand shown in FIG. 2; and

FIG. 4 is a side elevational view, partly in cross section and partially broken away, of the combined telephone handset and desk stand shown in FIG. 1.

The dominant features of my new design reside in the portions shown in full lines on the drawing.

I claim:

The ornamental design for a combined telephone handset and desk stand, substantially as shown and described.
